Filed Nov. 5, 1969, Ser. No. 19,948

Term of patent 14 years

Int. Cl. D30—02

U.S. Cl. D30—1

FIG. 1 is a perspective view illustrating a first embodiment of my design;

FIG. 2 is a top plan view of the design of FIG. 1;

FIG. 3 is a side elevation view of the design of FIG. 1, it being understood that both sides of the design are the same;

FIG. 4 is a rear end elevation of the design of FIG. 1;

FIG. 5 is a bottom plan view of the design of FIG. 1;

FIG. 6 is a cross-sectional view of the design of FIG. 1 illustrating more clearly the exterior configuration of the bottom and front and rear of the design, taken on line 6-6 of FIG. 2;

FIG. 7 is a perspective view of an alternate embodiment of my design in which a plurality of bee hives are stacked upon one another, it being understood that the side not illustrated is the same as the illustrated side thereof;

FIG. 8 is a front elevation view of the embodiment shown in FIG. 7; and

FIG. 9 is a rear elevational view of the embodiment of FIG. 7, it being understood that the top and bottom of the embodiment of FIG. 7 are the same as the top and bottom of the embodiment of FIG. 1.

I claim:

The ornamental design for a foamed plastic bee hive, as shown and described.
